UNITED STATES PATENT OFFICE.

HARRY LYON, OF HOLBROOK, MASSACHUSETTS.

DESIGN FOR A SHOE OR SIMILAR ARTICLE.

Application filed May 20, 1925. Serial No. 13,510. Term of patent 14 years.

To all whom it may concern:

Be it known that I, HARRY LYON, a citizen of the United States, residing at Holbrook, in the county of Norfolk and State of Massachusetts, have invented a new, original, and ornamental Design for Shoe or Similar Article, of which the following is a specification, reference being had to the accompanying drawing, forming part thereof.

The figure of the drawing represents in perspective a shoe or similar article showing this design, the dominant feature of which is presented by the upper face of the welt.

I claim:

The ornamental design for a shoe or similar article as shown.

HARRY LYON.
